Primary Examiner — Kevin Rudzinski*Assistant Examiner* — John Reickel*(74) Attorney, Agent, or Firm* — NSIP Law(57) **CLAIM**

The ornamental design for a display screen or portion thereof with graphical user interface, as shown and described.

DESCRIPTION

The sole FIGURE is a front view of a display screen or portion thereof with graphical user interface, showing our new design.

The broken lines are for environmental purposes only and form no part of the claimed design.
